Inventor:

A. G. Mack.

United States Patent Office.

A. G. MACK, OF ROCHESTER, NEW YORK, ASSIGNOR TO HIMSELF AND GEORGE SHELTON, OF SAME PLACE.

Letters Patent No. 97,942, dated December 14, 1869.

IMPROVED WARDROBE.

The Schedule referred to in these Letters Patent and making part of the same

To all whom it may concern:

Be it known that I, A. G. MACK, of Rochester, in the county of Monroe, and State of New York, have invented certain new and useful Improvements in Combination-Wardrobes; and I do hereby declare that the following is a full, clear, and exact description thereof, reference being had to the accompanying drawing, making part of this specification, in which—

Figure 1 is a front elevation, looking in the direction of the arrow, fig. 2.

Figure 2 is a transverse section, at the dotted line *x*, fig. 1.

Figure 3 is a plan view of a portion of the top.

The object of my invention, the nature of which will be understood by reference to the specification and drawings, is to provide an ornamental wardrobe, which shall combine the conveniences of a closet, bureau, and toilet-stand, and, at the same time, occupy but little space.

To enable others to make and use my invention, I will describe its construction.

The case A, figs. 1 and 2, is so constructed that the rear portion shall fit into the corner of a room, while the front projects somewhat, and is of polygonal section, as shown in fig. 2, the number of sides varying, according to the taste of the purchaser, from two upward. This front may be composed of any ornamental wood, having mouldings to correspond with the finish of the room in which it is placed, if desirable.

Within this case, a wardrobe-reel, B, is located, revolving upon pivots at top and bottom, and provided with arms *b*, to which is secured a number of hooks, *a*, to receive articles of clothing.

The door *d*, in one of the sides or sections of the case, opens into the interior of the latter, through which access may be had to any arm of the reel, by swinging the latter upon its axis.

The arms *b* are secured to the spindle, at a suitable height from the bottom of the case A, and may be six or more in number, as desired.

The hooks are located so that those on adjacent sides of the arms shall not be opposite one another, for greater convenience in hanging up or removing articles.

It will be seen, that by this arrangement, a large quantity of clothing can be hung up in a comparatively small space, while it is all easily accessible.

To one section of the case, shelves *G* may be at-

tached, for the reception of toilet-articles, and a mirror, *H*, is suspended over them. If desirable, drawers may be provided under these shelves.

The remaining sections of the front have shelf-closets *C*, made of a suitable depth, and accessible by doors *c*, similar to *d*. One of these closets may have a rack for umbrellas, as shown in fig. 1.

Below the closets *C*, drawers *D* are introduced, under a false bottom in the case A, which answer the same purposes as the drawer of a bureau.

In the two outside sections, box-cupboards *D'*, for boots, shoes, and similar articles, may take the place of the drawers, extending into the case as far as is desirable.

A writing-desk may also be secured to one of the sections.

To facilitate the removal and shipment of the wardrobe, the rear portion is made separate from the front, the line of division being parallel with the polygonal outline, as shown in dotted lines in fig. 2. The two parts may be attached to each other by hooks and staples at the sides.

A gudgeon, cast upon the plate *f*, fig. 3, and projecting into the case A, enters a ferrule on the end of the reel-spindle.

By removing the plate *f*, the reel *B* may be taken out for any purpose.

The sides of the rear portion may be hinged at the angle *g*, fig. 2, so as to fold, if desirable, for packing or shipment.

It will be observed, that while this wardrobe possesses all the conveniences of a closet, bureau, hook-case, and dressing-case, it will occupy but little space, and be an ornamental object in any room. It will be especially valuable in large cities, where, in many dwellings, it is impracticable to have closets connected with dressing or sleeping-rooms.

I claim no part of the invention shown in the patent of J. Moser of 1867; but

What I claim as my invention, and desire to secure by Letters Patent, is—

The skeleton-reel *B*, in combination with the fixed shelf-closets *C* and drawers *D*, of corner cabinet-cases, as set forth.

A. G. MACK.
